H. C. BASCOM.
COOKING STOVE.

No. 20,464.

Patented Jan. 6, 1891.

20,464. — COOKING STOVE. — *Henry Clay Bascom, Lansingburg, N. Y.* Application filed December 3, 1890. Serial No. 373,491. Term of patent 7 years.

UNITED STATES PATENT OFFICE.

HENRY CLAY BASCOM, OF LANSINGBURG, NEW YORK.

DESIGN FOR A COOKING-STOVE.

SPECIFICATION forming part of Design No. 20,464, dated January 6, 1891.

Application filed December 3, 1890. Serial No. 373,491. Term of patent 7 years.

To all whom it may concern:

Be it known that I, HENRY CLAY BASCOM, a citizen of the United States, residing in the village of Lansingburg, in the county of Rensselaer and State of New York, have invented and produced a new and original Design for Cooking-Stoves, of which the following is a specification, reference being had to the accompanying photograph of a cooking-stove

10 having said design.

My said design relates to the ornamentation of a cooking-stove, and the leading feature thereof is an ornamentation having an outer annular series of outwardly-spreading 15 radially-inclined volutes, substantially as shown in the aforesaid photograph.

In said photograph, A represents an oven-door of the stove; B, a side door or panel at the end of the fire-box; C, a panel on the side 20 plate D of the rear extension, and E the legs.

Each one of the said doors, panels, and legs has on it an ornamentation having an outer annular series of outwardly-spreading radially-inclined volutes, as a, a', or a².

25 The oven-door A has on it the annular series of outwardly-spreading radially-inclined volutes a, surrounding a circular ornamented portion b.

Each of the side panels B and C has thereon 30 an annular series of outwardly-spreading radially-inclined volutes a', surrounding a central ornament b'.

The leg E has on it an annular series of

outwardly-spreading radially-inclined volutes a², surrounding a central ornament b². 35

What I claim is—

1. The design for a cooking-stove herein shown and described, the same comprising ornamentations having outer annular series of outwardly-spreading radially-inclined volutes disposed upon the doors and panels of the stove, as set forth. 40

2. In a design for a cooking-stove, the design for the oven-door herein shown and described, embracing an ornamentation having an outer annular series of outwardly-spreading radially-inclined volutes, as set forth. 45

3. In a design for a cooking-stove, the design for a side panel herein shown and described, comprising an ornamentation having an outer annular series of outwardly-spreading radially-inclined volutes, as set forth. 50

4. In a design for a cooking-stove, the ornamental design for a leg herein shown and described, comprising an ornamentation having an outer annular series of outwardly-spreading radially-inclined volutes, as set forth. 55

In testimony whereof I hereunto set my hand, in the presence of two subscribing witnesses, this 1st day of December, 1890.

II. CLAY BASCOM.

Witnesses:

CHARLES H. BENEDICT,
CHESTER BASCOM.
